UNITED STATES PATENT OFFICE.

ANDREW SMITH, OF SAN MATEO, CALIFORNIA, ASSIGNOR TO SMITH METAL PERFORATING COMPANY, OF SAN MATEO COUNTY, CALIFORNIA.

PROCESS FOR MAKING WELL-CASING.

1,027,917.

Specification of Letters Patent.

Patented May 28, 1912.

Continuation of application Serial No. 489,642, filed April 13, 1909. This application filed June 2, 1911.
Serial No. 630,887.

To all whom it may concern:

Be it known that I, ANDREW SMITH, citizen of the United States, residing at San Mateo, in the county of San Mateo and 5 State of California, have invented a new and useful Process for Making Well-Casing, of which the following is a specification in such full and clear terms as will enable those skilled in the art to construct and use 10 the same.

This invention relates to a process of producing slotted metal plates for use in the production of well casing, drain tiling, etc., the object being to produce a narrow slot 15 sufficiently fine to exclude fine sand in metal plates of any desired thickness.

It will be understood by those skilled in the art that it is not possible by the ordinary punching processes to produce openings in a metal plate of the harder metals with a punch whose smallest dimension is less than the thickness of the plate to be punched, such punches being unable to stand the repeated punching operations.

25 This invention therefore seeks to provide means whereby an indefinite number of slots narrower than the thickness of the metal sheet may be produced therein with punches which will withstand the heaviest usage.

30 Another object of the invention is to produce a slotted metal sheet which will have the walls of the slots comparatively smooth, thereby increasing the life of the metal sheet since with metal sheets having fine 35 openings broken therein in the production of the so-called "cracked casings", the roughened edges of the openings begin to rust very quickly and in a short time the opening is enlarged so much as to be practically useless for the purposes intended.

Another object of forming casing in the manner herein described lies in the fact that the smooth walled slots produced in the casing are very easily galvanized and may 45 be so galvanized after the casing has been finished without danger of stopping up the slots so formed.

In the drawings in which the same numeral of reference is applied to the same portion throughout the several views, Figure 1 50 is a side elevation of a portion of well casing slotted in the manner herein described, Fig. 2 is a plan view thereof, Fig. 3 is a plan of a plate which has been punched to

form projections on one side thereof, Fig. 4 55 is a side elevation of the plate shown in the Fig. 3, Fig. 5 is a sectional view of the plate shown in Fig. 3, Fig. 6 is a plan view of a plate which has been produced by forming projections on opposite sides thereof, the 60 metal adjacent the slits formed being moved in opposite direction something more than one-half the thickness of the plate, Fig. 7 is a side elevation of the plate shown in Fig. 6, Fig. 8 is a sectional view of the plate 65 shown in Fig. 6, Fig. 9 is a plan view of a plate which has been formed by moving the metal on opposite sides of the several slits parallel to its initial position as would be the case with a straight end punch, save that 70 the ends of the projection thus formed are rounded, Fig. 10 is a view of the plate shown in Fig. 9 in end elevation, Fig. 11 is a view of the plate shown in Fig. 9 in side elevation, Fig. 12 is a sectional view of the 75 plate shown in Fig. 9, Fig. 13 is a plan view of any one of the plates above described, after it has been upset and the projections formed therein rolled back into place, and Fig. 14 is a sectional view of the 80 plate shown in Fig. 13, with the upsetting adjacent the several slits formed therein exaggerated for purposes of illustration.

The numeral 1 represents a portion of well casing in which there are a series of 85 slots 2 formed, said slots extending around the casing in several parallel series.

In Fig. 3 a plate 3 has projections 4 formed therein, said projections being pressed up from the body of the metal forming the plate slightly more than the total thickness of the plate, the total width of the metal distorted by the punch being greater than the thickness of the plate, whereby it is possible to use a very strong 95 and solid punch. This plate is shown in side elevation and in section in Figs. 4 and 5.

In Fig. 6 there is shown a plate 5 having projections 6 formed therein on one side 100 and projections 7 formed therein on the reverse side, the object being to move the metal adjacent the slots as short a distance as possible, thus stretching it the minimum amount in the production of the projections. Such a plate as this is shown further in side elevation and in section in Figs. 7 and 8.

The forms of casing shown in Figs. 1 to

8, inclusive, have been disclosed in my co-pending application Serial Number 489,642, of which the present case forms a continuation.

5 In Fig. 9 there is shown a plate 8 having projections 9 and 10 formed therein, the former being on one side of the metal sheet while the latter are on the opposite side thereof. This form of projection is produced by means of a straight end punch having its corners curved to prevent cutting the metal at the end of the punch.

10 After the production of any one of the above mentioned plates, the punch forming the projections therein may be struck laterally to upset the edges of each of the projections thus produced, as indicated at 11 on the plate 8. After the edges of the projections have been upset, the plates may then 15 be passed through rolls which will again return the projections to the plane of the plate, thus making a perfectly smooth plate save for the slight projections at the edges of the projections where they have been upset. Such a plate is shown in plan in Fig. 13 and in sectional view in Fig. 14, the amount of the upsetting being exaggerated in the latter figure for the purpose of illustration.

20 It will of course be understood that since it is contemplated that this product shall exclude from the pipe all fine materials such as sand, the openings produced must be very small. In the case of oil wells, the 25 openings are about one inch long by one-sixteenth of an inch wide in three-eighths to one-half inch casing, while in the case of water wells the openings are about one-thirty-second of an inch in width or less, 30 as may be determined necessary owing to the condition of the soil in which the well is bored, while in the case of drain tiling, the slots will be from one-thirty-second of an inch downwardly depending upon the 35 soil in which the tiling is placed.

40 It will be obvious that the plate may be used with or without returning the projections to the plane of the sheet, the only requisite being that the upsetting be of such 45 an amount as is deemed necessary to produce the desired slits in the finished plate.

Having thus described my invention what I claim as new and desire to secure by Let-

ters Patent of the United States, modifications within the scope of the claims being 55 expressly reserved, is as follows:

1. The process of making plates for well casings comprising forming a plurality of slits in a plate by a shearing operation and laterally displacing the metal upon one side 60 of each slit, thus causing the edges to project beyond the plane of the plate, and then upsetting the projecting edges.

2. The process of making plates for well casings comprising forming a plurality of 65 slits in a plate by a shearing operation and laterally displacing the metal upon one side of each slit, thus causing the edges to project beyond the plane of the plate, then upsetting the projecting edges, and pressing 70 the laterally displaced portions into the plane of the metal sheet.

3. In a process for the production of well casing, forming a series of projections in a metal plate by pressing adjacent portions 75 thereof on opposite sides in opposite directions a distance slightly more than one-half the thickness of the metal plate, thus forming a slit between said portions, as set forth.

4. In a process for the production of well 80 casing, forming a series of projections in a metal plate by pressing adjacent portions thereof on opposite sides in opposite directions a distance slightly more than one-half the thickness of the metal plate, thus forming 85 a slot between said portions, and upsetting the edges of the projections thus formed, as set forth.

5. In a process for production of well casing, forming a series of projections in 90 a metal plate by pressing portions thereof on opposite sides in opposite directions a distance slightly more than one-half the thickness of the metal plate, thus forming a slit between said portions, upsetting the 95 edges thus formed, and then pressing the projections back into the general plane of the sheet, as set forth.

In testimony whereof I have hereunto set my hand this 23rd day of May A. D. 1911, 100 in the presence of the two subscribed witnesses.

ANDREW SMITH.
